VERNER F. DAVIS, OF WEST ORANGE, NEW JERSEY, ASSIGNOR TO ATLAS VALVE COMPANY, OF NEWARK, NEW JERSEY, A CORPORATION OF NEW JERSEY

STEAM FLOW REGULATION

Application filed December 5, 1930. Serial No. 500,206.

This invention relates to steam flow regulation and has reference more particularly to a system or apparatus comprising valves and regulating means so combined and inter-related as to give the regulation of steam flow which is the purpose of the invention.

The invention is intended more especially for use in connection with any apparatus or process wherein relatively low pressure steam is desired to be delivered or used at a substantially constant pressure, and wherein fluctuations are likely to occur, whether because of variations in demand or because the steam supply comprises a fluctuating low pressure source, and wherein a second source of steam is available having pressure substantially higher than the constant pressure required for the chemical or other process or apparatus in which the delivered steam is to be utilized or consumed. A particular use is supplemental to a power or other plant, wherein a turbine or other engine or apparatus delivers exhaust or back pressure steam in limited quantities and at relatively low but possibly fluctuating pressure, and wherein the initial source of steam or boiler is available for fortifying the exhaust steam pressure for the purposes of the invention.

The general object of the invention therefore is to permit the continuous and steady supply and utilization of exhaust or other low pressure steam at a substantially constant pressure for the purposes in hand notwithstanding fluctuations in rate or supply or demand. A more particular object is to afford the desired regulation through means of a controlled connection to the atmosphere and a controlled connection from a higher pressure source, so that one or the other of such connections may be operated, as the delivered pressure varies or tends to vary, to restore or maintain it at the desired constant pressure.

A further object is to afford such control from the low pressure passage or main itself as it delivers to the point of consumption, and to operate the control means in a cooperative manner to avoid the possibility at any time of simultaneously opening the connection both to the atmosphere and from the high

pressure source, with consequent escape and waste of high pressure steam.

Other objects and advantages of the invention will be pointed out in the hereinafter following description of one or more embodiments of the invention or will be understood by those conversant with the subject. To the attainment of such objects and advantages the invention consists in the novel steam flow regulation apparatus and the novel features of operation, combination, arrangement and construction herein described or illustrated.

In the accompanying drawings Figure 1 is a general diagrammatic assembly view of the combined apparatus, which may be considered as taken in elevation view.

Figs. 2, 3 and 4, on a larger scale, are central sectional views of certain of the regulating and valve parts of the apparatus.

In referring to "steam" it is to be understood that the principles may be available for the regulation of flow of any fluid, especially any gas or vapor; and in referring to "water" in the regulating or hydraulic parts of the apparatus it is to be understood that any liquid is intended to be covered, and where in the claims reference to water or liquid is omitted it is intended to cover other regulating means or connections adapted to an equivalent purpose. In using the term "pipe" it is intended to include any sort of passage or flow connection. By exhausting or escaping to the "atmosphere", is included any point whereat the pressure is substantially less than the desired low pressure, and it may be subatmospheric pressure.

As a typical instance a boiler at about 100 pounds per square inch pressure may be operating turbines or engines discharging exhaust steam at a pressure of about 5 pounds, but possibly varying between 3 and 7 pounds, and it may be desired to utilize the discharged steam for process or for heating or other purposes, involving possible extensive fluctuations in demand, at say 4 pounds delivered pressure. The present invention will easily accomplish this object with such uniformity of delivered pressure as to avoid variations of more than $\frac{1}{2}$ pound above or below the desired pressure. The exhaust steam therefor

is usefully employed, without waste, and the utilized pressure is sufficiently steady for practical purposes. Additionally the consumption of fuel is substantially reduced, due to the steady and automatic action of the invention, tests showing a substantial saving in consumption of fuel under the boiler. A further advantage is the corrected uniformity and steadiness of operation of turbines or engines, due to steady back pressure 10 and resulting in increased efficiency.

The diagram Fig. 1 of the drawings shows a source of low pressure in the form of a pipe or back pressure main 10, leading for example from the exhaust of a turbine or other engine. The pipe 10 is shown leading to a fitting or T 11, which will be referred to later, and this in turn delivers to a fitting or T 12, from the first outlet of which extends the delivery or final output pipe 13 which 15 conducts the low pressure steam to the place of consumption. The low pressure pipes 10 and 13 are substantially a continuous passage, and carry steam which is subject to possible fluctuations in flow and pressure due to 20 variations in supply or demand.

Beyond the second outlet of the fitting 12 is shown a valve 14 which may take part in the control of the steam pressure delivered to the outgoing main 13, namely by letting off 25 or relieving excess pressure at proper times. The control valve 14 will be hereinafter referred to as a relief valve, and when open it discharges regulated quantities of steam to 30 an escape or waste pipe 15 which may deliver directly to atmosphere or other low pressure point.

The diagram shows also a source of high 35 pressure steam in the form of a pipe or main 18 leading for example from a boiler. This high pressure main is shown as supplying live steam through a control valve 19 to a connection or pipe 20 extending to the lateral inlet of the fitting 11, so that steam passing 40 through valve 19 is admitted to the back pressure main 10 and thence to the delivery main 13. The control valve 19 is intended to be operated at times of deficient pressure in the delivery main, being controlled to admit suitable quantities of high pressure steam 45 to make up the deficiency and bring the delivered pressure to the desired constant pressure, and it will be referred to as a make-up valve.

We thus have two incoming mains or pipes 50 10 and 18, one carrying low and the other high pressure, and two outgoing mains or pipes 13 and 15, one delivering low pressure to the point of consumption and the other discharging to atmosphere, the low pressure mains 55 10 and 13 being preferably permanently connected for continuous flow, while the high pressure main and the escape pipe respectively are controlled by the make-up 60 valve 19 and relief valve 14, which two valves

are controlled by this invention in a certain cooperation to insure the delivery through main 13 of substantially constant low pressure steam.

The two valves 14 and 19 may be steam 70 valves of various types of controllable construction. For example they may be substantially similar, and of the diaphragm controlled type. Fig. 2 indicates valve 14 in closed condition and Fig. 3 indicates valve 75 19 in open condition, corresponding with the positions shown in Fig. 1, on the assumption that the delivery pressure is for the moment deficient.

Each of the two control valves 14 and 19 80 may have substantially the following construction as shown in Figs. 2 and 3. A valve seat 22 is shown as formed in an interior wall. Opposite to the valve seat is shown a movable disk or gate 23, closed in valve 14 and Fig. 85 2 and open in valve 19 and Fig. 3. This disk is carried on a sliding stem 24 which extends through the valve stuffing box to an exterior point and thence through the upper frame of the valve to where it carries an enlarged 90 head 25, shown of mushroom form. A valve spring 26 presses against a fixed part of the valve casing and against the mushroom head of the stem, thus tending to open the valve. A diaphragm 27 is shown bearing on the head 95 25 and arranged to receive pressure tending to close the valve in opposition to the spring. The diaphragm is peripherally clamped by the stationary parts of the valve, which enclose above the diaphragm a chamber 28, the 100 inlet to which is by a nipple 29 at the top of the casing. When sufficient hydraulic or other pressure is admitted through the nipple 29 this can act upon the diaphragm in a well 105 known manner to effect a closing of the valve to a greater or less extent.

What may be termed a compound regulator, and which may be at a remote point from the valves 14 and 19, comprises a first 110 unit 31 and a second unit 32 shown in exterior view in Fig. 1. These are preferably 115 fluid operated and a supply pipe 33 is shown conducting fluid under a convenient head to the inlets of the two units, for example city water pressure, used as a motive force. Hydraulic or water pressure is the illustrated 120 means of communicating regulating movements to the control valves, and the diagram shows a water pipe 34 leading from the first unit to the valve 14 and a water pipe 35 leading from the second unit to the valve 19. When the fluid pressure is delivered by pipe 34 the valve 14 will be closed, as indicated in the figure, and vice 125 versa. When no pressure fluid is delivered through pipe 35 to valve 19 that valve will be open, and vice versa. As will be described the compound regulator hereof is 130 so actuated that either one or the other of 135

the valves 14 and 19 may be open partly or fully, or both may be tightly closed at the same time, but so that it is impossible that both of them may be open at the same time, which would tend to result in a wasteful flow of high pressure steam through both valves to the atmosphere.

The units 31 and 32 of the compound regulator are in the nature of relays or pilot valves or devices, and each may have a construction as follows. Each consists of a casing enclosing a primary or upper chamber 37 and a secondary or lower chamber 38 with an opening and valve seat 39 extending from the primary to the secondary chamber. A movable valve, disk or cone 40 is shown adapted to close the seat 39 or to retract and open communication between the chambers. This valve is shown as comprising a longitudinally slidable stem 41, the lower end of which slides within the bottom wall of the casing and projects to an exterior point. Each stem is formed with an interior passage connecting the secondary chamber with an exterior point, for allowing fluid escape and relieving the pressure in the chamber and the connecting pipe 34 or 35. Each valve member 40 is shown as provided with a spring 43 tending to close the valve or relay, while the means for opening or lifting the valve against the spring for admitting water pressure to the secondary chamber serves also to close the exterior relief exit of the valve stem. From the inlet point of water pipe 33 to each relay unit is a passage 44 leading up to the primary chamber 37. When therefore the valve member is lifted the water is admitted through the chambers to the pipe 34 or 35; when it is lowered fully the water is cut off, and when the stem passage is opened the pressure in 34 or 35 is relieved.

For actuating the two relay or pilot devices is shown a pressure responsive means operating through a device or lever 45 representative of a mechanical connection to the devices. It is shown as fulcrumed at a middle point 46, with weights 47 tending to lower the outer or right end, and adjusting weights 48 slidable to set the action.

In fixed guides 50 are movable pins 51 and 52 for the relay units 31 and 32 respectively, each actuated by the lever 45 and operating the valve members 40. Each pin is adapted to close its relay valve relief passage 42 before lifting and opening the valve, and vice versa, for example by its conical point entering the passage as it lifts. The two actuating pins and levers are so arranged that in a mid position both pins will be holding both relay valves partly lifted and open and holding the relief passages closed, so that both control valves 14 and 19 will receive water pressure and be closed; while a shift of the actuating lever in either direction will drop one pin and lift the other, thus closing and relieving the pressure in one of the pipes 34 or

35 and allowing the corresponding control valve 14 or 19 to open, and vice versa. Fig. 4 shows in full lines the lever swung to extreme position, for closing the relay valve 31, and opening its relief 42 to allow the opening of make-up valve 19, while the dotted lines show the mid position, in which both relay valves 31 and 32 will be partly open and both control valves 14 and 19 wholly closed.

The pressure responsive devices may be as follows. The lever 45, at the same end as the unit 32, has a swivel connection 54 to a head 55 cooperating with a diaphragm 56 at the upper side of a chamber 57 formed in the fixed frame, with inlet nipple 58. A pipe 59 extends from the low pressure part of the steam apparatus to the nipple 58 so that, through the diaphragm, pressure fluctuations are translated promptly into movements of the actuator lever between its several positions. The pipe 59 may contain a gage 60 showing the pressure, and a blow off 61 for removing sediment. The waste water relieved from the units 31 and 32 may be directed to and drained by a drain pipe 63.

A modification of the above described structure which has been successfully employed consists in replacing the control valves 14 and 19, or one of them with a different type of steam valve having balanced pressures on the movable parts and being thus more readily and accurately adjusted in the case of higher pressures. In such case the transmission of control from the units or relays 31 and 32 may comprise mechanical as distinguished from hydraulic transmitting means. For example, taking the unit or relay 31, the water delivered from it, instead of passing directly to the control valve 14, may be passed to the lower end of a vertical cylinder, within which moves a piston having a relatively large stem extending through a stuffing box at the upper end, and the stem connected by cable with the accessible part of the control valve. By this arrangement when the relay or pilot valve 31 is open, for flow of water, the water will lift the piston and thereby cause the closing of the control valve, while, when the water is shut off from the cylinder, and the cylinder relieved, the normal water pressure at the top of the piston will force the piston down and thus open the control valve. In connection with this arrangement there may be an automatically shiftable weight on the lever 45, arranged to be shifted by the lifting of the piston to move the weight outward or toward the right end, and vice versa, giving a more sensitive action and controlled lever position.

The operation of the invention has been indicated above, but may advantageously be restated as follows. If and when the back pressure from main 10 happens to be correct for the purposes of consumption, the dia-

phragm 56 will operate to maintain the lever 45 in mid or neutral position. In this position both of the relays 31 and 32 are partly open, and their relief passages 42 of course closed by pins 51. Therefore pressure will be communicated to both control valves 14 and 19 and they will both be held closed, so that there is no modification of the pressure passing from main 10 to the delivery main 13.

When, for example, the back pressure however is deficient, due to excess demand or otherwise, the pressure must be built up. The outer or right end of the lever will be allowed to descend, due to the reduced pressure under the diaphragm, thus closing the relay 32 and more widely opening the relay 31 and at the same time opening the relief passage 42 below the relay 32. Immediately the make-up valve 19 will commence to open, and the pressure will commence to build up. As soon as the desired pressure is restored, which may be during the readjustment, the diaphragm will restore the lever to or slightly beyond mid position, and the water will be trapped in the pipe 35, and the make-up valve 19 will be held in the adjustment reached by it. If the additional steam thus supplied constitutes the desired correction the parts may remain indefinitely in such position. This adjustment however may be only momentary, in case the tendency is to build the pressure up beyond the desired amount.

In a sense there is a lap action by which any adjustment may be held by the water trapped in the pipes leading to the control valves for an appreciable time. Thus, as a change of controlled pressure causes the right end of the lever 45 to rise from the position shown, the pin 52 will reach the stem 41 and close the passage 42 before reaching its mid position. Thereafter it encounters the resistance of the valve 40 to lifting, so that only after this is overcome will the parts rise further. On the reverse adjustment the reverse action of course takes place, and during the lap period the water in pipe 35 is trapped, and holds the control valve 19 in its then adjusted condition, until a further change is required.

As soon as the steam pressure rises above the desired pressure, due to the supply exceeding the demand for steam, the lever will be shifted beyond its mid position by the further lifting of the diaphragm. It will be observed that the lap is quite small, so that if the lever has to be shifted from one extreme position to the other, the readjustments of the valves 14 and 19 will follow each other quite closely; there will be no substantial time interval, and the delivered pressure can be held quite closely to the desired amount. The lowering of the left end of the lever beyond mid position closes the relay 31 and opens the relief 42 below it. As a consequence the relief control valve 14 is opened,

the make-up valve 19 having already been closed, and the excess pressure is discharged to the atmosphere, until the correct pressure is restored. As before, the restoring of the lever to mid position may trap the water in pipe 34 and hold the relief valve 14 in a partly open condition, thus continuously relieving the excess pressure, as long as the supply and demand conditions remain the same.

In any reversal of adjustment the lever must pass through its mid or neutral adjustment, wherein both of the relay valves are open, both of their relief passages closed and therefore both of the control valves 14 and 19 maintained closed.

Obviously a reversal might be made wherein the passing of regulating fluid by each relay valve would effect the opening instead of the closing of the corresponding control valve, in which case the neutral or mid position of the actuator would be such that both relay valves would be closed, and both relief passages open, to discharge the regulating fluid, and thereby permit the closing of both control valves. It is preferable however to have the control valves self opening and only close them by the passing of the regulating fluid. The regulating fluid is preferably a liquid or water rather than an elastic fluid such as steam, since hydraulic regulation permits the actuator to close one relay valve, without opening its relief passage, thereby trapping the liquid and holding the control valve, for example in a slightly open position for an indefinite time if this happens to result in the correct delivered steam pressure.

There has thus been described a steam flow regulation apparatus accomplishing the objects and advantages as already referred to and embodying the principles of the invention; but since various matters of operation, combination, arrangement and construction may be modified without departing from the principles, it is not intended to limit the invention to such matters except so far as set forth in the appended claims.

What is claimed is:

1. In steam flow regulation apparatus for delivering at substantially constant low pressure, the combination of a low pressure supply passage, a low pressure delivery passage connected therewith, a high pressure passage with control make-up valve adapted to discharge into one of said low pressure passages, a relief passage with control relief valve adapted to discharge from one of said low pressure passages, and automatic regulating means for said control valves, comprising a first device for opening and closing the relief valve and locking it closed, a second device for closing and opening the make-up valve, a pressure responsive actuator operated by variations of delivered pressure between a neutral position and to positions at opposite sides thereof, and connections from

said actuator to both of said devices whereby in neutral position it adjusts both devices to close and lock both control valves, but in one side position corresponding to deficient delivered pressure it adjusts said devices to open the make-up valve and close the relief valve, while in the other side position corresponding to excess delivered pressure it adjusts said devices to close the make-up valve and open the relief valve.

10 2. In steam flow regulation apparatus for delivering at substantially constant low pressure, the combination of a low pressure supply passage, a low pressure delivery passage, a high pressure passage with control make-up valve adapted to discharge into one of said low pressure passages, a relief passage with control relief valve adapted to discharge from one of said low pressure passages, and regulating means for said control valves, comprising a regulating fluid source, a first relay fluid valve connected with said source for allowing fluid to pass for reversing the setting of the relief valve, and with a relief passage opened when the relay valve is closed, a second relay fluid valve connected with said source for allowing fluid to pass for reversing the setting of the make-up valve, and with a relief passage opened when the relay valve is closed, and a pressure responsive actuator shiftable between a neutral and opposite side positions by variations of delivered pressure, and operating to actuate both of said relay valves in a manner to open one of them and close the other when the delivered pressure becomes deficient, and to reverse the positions when the delivered pressure becomes excessive, and to lock both relay valves closed when in neutral position.

40 3. Apparatus as in claim 2 and wherein the actuator has a mid position wherein both relays are in positions to close both control valves.

45 4. In steam flow regulation apparatus for delivering at substantially constant low pressure, the combination of a low pressure supply passage, a low pressure delivery passage, a high pressure passage with a self-opening control make-up valve adapted to discharge into one of said low pressure passages, a relief passage with a self-opening control relief valve adapted to discharge from one of said low pressure passages, and regulating means for said control valves, comprising a regulating fluid source, a first fluid valve connected with said source and adapted when open to pass fluid for causing the closing of the relief valve, a second fluid valve connected with said source and adapted when open to pass fluid for causing the closing of the make-up valve, a relief passage associated with each of said fluid valves and adapted to relieve the fluid when the fluid valve is closed to permit the control valve to open, and a pressure responsive actuator shiftable

between different positions by variations of delivered pressure, and operating to open the first fluid valve and close the second when the delivered pressure becomes deficient, and to close the first fluid valve and open the second when the delivered pressure becomes excessive.

5. Apparatus as in claim 4 and wherein the actuator has a mid or neutral position wherein both fluid valves are open and therefore both control valves are closed.

In testimony whereof, this specification has been duly signed by:

VERNER F. DAVIS.
